(57) **CLAIM**

The ornamental design for a composite sensor for indoor environmental and biological information, as shown and described.

DESCRIPTION

FIG. 1. is a first perspective view of a composite sensor for indoor environmental and biological information showing our new design;

FIG. 2. is a second perspective view thereof;

FIG. 3. is a front view thereof;

FIG. 4. is a rear view thereof;

FIG. 5. is a left side view thereof;

FIG. 6. is a right side view thereof;

FIG. 7. is a top plan view thereof;

FIG. 8. is a bottom view thereof;

FIG. 9. is an enlarged view of a part 9-9 in FIG. 3; and,

FIG. 10. is an enlarged view of a part 10-10 in FIG. 3.

The broken line showing of the composite sensor for indoor environmental and biological information is included for the purpose of illustrating portions of the composite sensor for
